Harry Langsam

ATTORNEY.

1. A chair or seat which may be converted into a bed, comprising a pair of parallel legs 10, 10 connected by cross bars to form a first frame pivoted at 11 to a second pair of parallel frames 12, 12 to form a second frame, the pivot 11 being close to the end 10A of leg 10 and the end 11A of leg 12, the second frame 12, 12 being pivoted at 13 to the first frame 10, 10, the second frame 12, 12 being adapted to be tilted at a predetermined angle with respect to the first frame 10, 10, the second frame 12, 12 being supported by a pair of stays or braces 14, 14, each having one end pivoted at 15 to the leg 10 and a cross member 14A joining the other ends of the braces 14, 14, the second frame 12, 12 being adapted to rest in one of the notches 12A on the leg 12 whereby the leg 10 is tilted at a predetermined angle with respect to the leg 12, the end 10A of leg 10 and the end 12B of leg 12 resting upon the ground, the side legs 10, 12 being identical, any reference to a singular side leg describing both side legs.

UNITED STATES PATENT OFFICE

2,611,418

CONVERTIBLE RECLINING CHAIR AND COT

Leon Antelman, Philadelphia, Pa.

Application February 13, 1948, Serial No. 8,208

1 Claim. (Cl. 155—45)

1

2

My invention relates to a seat and relates particularly to a folding seat which may be converted into a bed without the addition of any parts.

Adjustable folding chairs have been manufactured and so have holding seats which are convertible to a bed but the prior art devices lack (1) simplicity, and (2) simplicity to convert a reclining chair to a bed.

It is, therefore, an object of my invention to provide a collapsible seat which may be converted from a seat to a bed and which also may be adjusted as a seat.

Another object of my invention is to provide a convertible seat into a bed by the simple expedient of changing the angle of the two pivoted members on each side with respect to the ground.

Other objects of my invention are to provide an improved device of the character described, that is easily and economically produced, which is sturdy in construction, and which is highly efficient in operation.

With the above and related objects in view, my invention consists in the details of construction and combination of parts, as will be more fully understood from the following description, when read in conjunction with the accompanying drawings in which:

Fig. 1 is a side elevation view of a convertible folding chair and bed embodying my invention with the unit in a reclining chair position.

Fig. 2 is a side elevational view of the convertible folding chair and bed of Fig. 1 with the unit shown in a bed position.

Fig. 3 is a top view of the chair position illustrated in Fig. 1.

Fig. 4 is a top view of the bed position illustrated in Fig. 4.

Fig. 5 is a front view of the chair position illustrated in Fig. 1, see line 5—5 of Fig. 1.

Fig. 6 is a rear view of the chair position illustrated in Fig. 1, see line 6—6 of Fig. 1.

Fig. 7 is a front view of the bed position shown in Fig. 2, see line 7—7 of Fig. 2.

Fig. 8 is a rear view of the bed position shown in Fig. 2, see line 8—8 of Fig. 2.

Fig. 9 is a side view of the convertible folding chair and bed in a collapsed or folded position.

Referring now in greater detail to the drawings wherein similar reference characters refer to similar parts, my convertible chair and bed comprises a pair of parallel legs 10, 10 connected by cross bars to form a first frame pivoted at 11 to a second pair of parallel frames 12, 12 to form a second frame. It is to be observed that the pivot 11 is close to the end 10A of leg 10 and the end 11A of leg 12, the second frame 12, 12 being pivoted at 13 to the first frame 10, 10, the second frame 12, 12 being adapted to be tilted at a predetermined angle with respect to the first frame 10, 10, the second frame 12, 12 being supported by a pair of stays or braces 14, 14, each having one end pivoted at 15 to the leg 10 and a cross member 14A joining the other ends of the braces 14, 14, the second frame 12, 12 being adapted to rest in one of the notches 12A on the leg 12 whereby the leg 10 is tilted at a predetermined angle with respect to the leg 12, the end 10A of leg 10 and the end 12B of leg 12 resting upon the ground, the side legs 10, 12 being identical, any reference to a singular side leg describing both side legs.

12A of leg 12. A pair of stays or braces 14, 14 each has one end pivoted at 15 to the leg 10 and a cross member 14A joining the other ends of the braces 14, 14 is adapted to rest in one of the notches 12A on the leg 12 whereby the leg 10 is tilted at a predetermined angle with respect to the leg 12. In the position indicated in Fig. 1, the end 10A of leg 10 and the end 12B of leg 12 rest upon the ground. Since the side legs are identical any reference to a singular side leg describes both side legs.

The fabric or canvas 26 forms the seat and back rest itself and has one end securely attached to the cross strut 13A at one end of the frame 12—12 and the other end securely attached to the cross strut 13B at the opposite end of the frame 12—12 with the fabric passing over the cross strut 10C at the upper end 10B of the frame 10—10. The length of the seat fabric is such that when the chair is converted to a cot the fabric will be held taut so that the user may recline in a horizontal position between the cross bars 10C and 13A.

A suitable arm rest 24 is pivotally mounted at 24A on each of the frames 10 and the arm rest has a cut-out portion to interfit with the brace 14 whereby movement of the arm rest is arrested in one direction but not in the other.

A combined head rest and awning frame is pivoted at 18 to the end 10B of frame 10—10 and comprises a pair of side bars 20, 22 connected by a bar 21. The combined head rest and awning fabric A passes over bar 21 and has its ends attached at 20A to a cross bar at the free end of the frame 20—20 and a cross bar at the free end of the frame 22—22. It should be observed that the awning portion of the fabric A is attached to the frame 20—20 whereas the head rest portion is attached to the frame 22—22.

In Figs. 1, 3, 5 and 6, I have shown the unit in a chair position and to convert the chair to a bed or cot I swing the legs 10 approximately 90° to the left as Fig. 1 is viewed; however, in the position shown in Fig. 2 the end 10A still engages the ground. However, end 12A is shifted from an elevated to a ground position and end 12B is elevated from a ground position, meanwhile,

brace 14 is swung around its pivot 15 to a ground engaging position and braced against upward movement from the ground by the awning brace 20 with the head rest portion of the fabric A taking a position over one end of the cot fabric 26.

The arm rest 24 does not take any part in the conversion from chair to cot. In the position shown in Fig. 1 the arm rest 24 has one end abut

the brace 14 while in Fig. 2 the arm rest swings freely about its pivot 24A.

In Fig. 1 the frame 20—20 is held in position by virtue of short arms 20B which are mounted to tightly embrace the rod 18.

The entire unit may be folded to a substantially single thickness by collapsing all of the parts on the first frame as illustrated in Fig. 9.

Although my invention has been described in considerable detail, such description is intended as being illustrative rather than limiting, since the invention may be variously embodied, and the scope of the invention is to be determined as claimed.

I claim as my invention:

A combined collapsible chair and cot, comprising a frame in crossed relation to and pivoted to a second frame said frames each extending at an inclination to the ground, braces having ends pivotally connected to the first named frame, and having other ends adjustably supported upon the second frame, a strip of fabric connected at one end to the top of one frame extending over the top of said first frame and secured to the bottom of said second named frame, said frames being adapted to be rotated about the points of engagement of the first frame upon the ground and spread apart to extend at reverse inclinations and

the braces detached and swung down to engage the ground to form a cot frame, including a combined awning and head rest pivotally connected to the upper end of said first frame, said awning being substantially perpendicular to said head rest, and the free end of said awning being adapted to swing about its pivotal connection to engage said braces to form a head end support when the device is extended to form a cot, the headrest overlying one end of the cot, and the awning alone forming a canopy when the device is converted to a chair.
